UNITED STATES PATENT OFFICE.

WILLIAM E. GREENAWALT, OF DENVER, COLORADO.

METALLURGICAL APPARATUS.

Application filed July 19, 1921. Serial No. 485,884.

To all whom it may concern:

Be it known that I, WILLIAM E. GREENAWALT, a citizen of the United States, residing in the city and county of Denver and 5 State of Colorado, have invented certain new and useful Improvements in Metallurgical Apparatus, of which the following is a specification.

The invention has for its object the effective treatment of liquids with gases. It may conveniently be used in the precipitation of metals from solutions, in the reduction of ferric salts in the electrolysis of copper solutions containing salts of iron, and 15 in the treatment of ore pulps with gases, such as sulphur dioxide, or chlorine.

This application may be considered as an improvement or modification of Patents No. 1,347,088, July 20, 1920; No. 1,347,089, July 20, 1920; No. 1,353,995, September 28, 1920, especially the latter, in which is shown an electrolytic apparatus consisting of an electrolyzer and a reducing chamber to reduce, say, the ferric salts formed by the electrolysis of copper solutions containing salts of iron. The present application is concerned more with the details of the reducing chamber in the application of corrosive gases to corrosive liquids, or electrolytes, 30 although it is not intended to limit the apparatus to any particular use.

The apparatus can best be described by referring to the accompanying drawings, in which Fig. 1 shows a transverse section, 35 of the apparatus. Fig. 2 a longitudinal section. Fig. 3 a detail of a modified shaft arrangement. Fig. 4 a detail, in elevation, of one of the atomizers. Fig. 5, a detail, in section, of one of the atomizers. Fig. 6 a detail of the ribs, or projections, of the 40 atomizers on the line 6—6 of Fig. 4.

In the drawings, 1 is a tank adapted to contain the liquid to be treated, and 2 a cover engaging the tank to form a closed 45 chamber therewith. The tank is divided into longitudinal sections by the partitions 3, and, with the partitions 4, causes the liquid to flow through the tank in an up and down or in a sinuous course. Within each 50 section is a rotary impregnator 5, taken as a whole, consisting of a shaft 6, upon which are mounted the discs, or atomizers, 7, which, in the treatment of corrosive liquids and gases may be made of lead or some 55 other noncorrosive metal. The atomizers

are mounted on the shaft by having a fixed steel collar, or anchor, 8 toward one end of the shaft, outside of the tank, and lead collars 9 passing through a stuffing box 10 at the sides of the tank, and contacting with the hubs of the atomizers 7. On the opposite outside of the tank a split nut 11 is fitted to the threads 12 of the shaft so that by turning the nut, the various atomizer hubs and collars are compressed and made 60 rigid on the shaft so as to prevent any gas or liquid from getting to the unprotected shaft to destroy it or from getting into the bearing. The nut 11 is mounted on the shaft between the rotary spraying member 70 and the bearing 13, and the nut is preferably made with a considerable projection to prevent corrosive fluid which may escape from the chamber through the stuffing box from getting into the bearing or from getting to the exposed steel shaft outside of the chamber. The shaft is mounted on the bearings 13 and driven by the motor 16 and the pulley 14. The other shafts may be driven by belts from the pulley 15. In this 75 way any number of shafts may be driven by one motor 16. The liquid is flowed into the tank through the inlet 17 and overflows through the outlet 18. The cover is preferably made in sections 2^a, so that any section 80 may be easily removed and the rotary mechanism lifted out bodily, when it is desired to repair or replace it. The gas inlet is indicated by 19 and the gas outlet by 20. The gas is preferably flowed through the chamber by suction made by an exhauster (not shown) communicating with the outlet pipe 20, so that if there is any leak there may be 85 a flow of air inwardly but no gas will escape to contaminate the atmosphere.

Within the chamber are scrubbers 21 consisting of a grating 22, filled with some permeable material such as coke or quartz 23, which serves to increase the surface exposure of the liquid to the gas, and may also serve to promote the reactions between the liquid and the gas. To still further increase the surface area of the liquid, baffles 24 are interposed between the atomizers 7 in the liquid, and baffles 25 in the gas over 100 the liquid. The atomizers are preferably provided with ribs 26, Figs. 4, 5, and 6, which tend to spray some of the liquid into the gas and submerge some of the gas in the liquid, when the shaft is rotated at the 105 110

proper speed. The ribs may be straight or curved. The arrangement shown in Fig. 4 is satisfactory and probably the best.

Fig. 3 shows a modified arrangement for 5 mounting the atomizers on the shaft. In this case the shaft 30 is hollow. The collar 31 is secured to the shaft. A steel collar 32, projecting slightly beyond the end of the shaft, rotates in the bearing at one end. 10 The lead collars 9, passing through the stuffing boxes of the tank, fill in the spaces between the atomizer hubs and the steel collar 32 and the steel collar 31. A rod 33 passes through the hollow shaft, with a nut 34 at 15 one, or both, ends. The atomizers and collars are compressed by turning the nut, and in this way the atomizers and collars are maintained rigid on the shaft and the joints are kept tight to protect the shaft from the 20 liquid and the gas.

The operation of the apparatus may be briefly described as follows: The liquid to be treated is flowed into the tank through the liquid inlet 17, and maintains its level 25 by overflowing through the outlet 18. It is given a sinuous course through the tank by the partitions 3 and 4, so that none of the liquid will be short circuited from the inlet to the outlet. The gas is introduced through 30 the gas inlet 19 and exhausted through the outlet 20. It flows horizontally through the chamber and through the scrubbers 21, which tend to equalize the flow. Both the scrubbers 21 and the baffles 25 greatly in- 35 crease the surface exposure of the liquid under treatment with the gas. The shaft is rotated at the proper speed to effectively spray the liquid into the gas over the liquid and submerge some of the gas in the liquid: 40 this speed will usually be several hundred revolutions per minute. The atomizers, rotating at such a speed, spray the liquid into the gas and into the scrubbers in a fine state of subdivision, while at the same time 45 some of the gas is submerged and distributed in the liquid in a fine state of subdivision. The gas passing through the permeable mass 50 of the scrubbers 21 comes in contact with the liquid, and the gassed liquid is immedi- ately and continuously washed back into the pool and replaced by other liquid from the pool. In this way the liquid is effectively treated with the gas as it passes from one section of the tank to the next, while at the 55 same time the steel shaft of the rotating mechanism is effectively protected from the corrosive action of both the liquid and the gas. The gas flows in a substantially horizontal direction through the chamber as also 60 through the permeable mass of coke, quartz, or other material within the chamber. The time of treatment will depend on the volume of the liquid and its rate of flow through the chamber. Ordinarily it will be desir- 65 able to have a large volume of solution un-

der treatment, and the time can be regulated largely by the rate of flow. The chambers are preferably made fairly deep, depending on the volume of liquid to be treated and the results desired. A considerable depth 70 of liquid will be the most economical way to get a large volume of liquid under continuous treatment.

The volume of liquid sprayed into the gaseous atmosphere in the chamber will depend largely on the speed of rotation and the amount of submergence of the periphery of the discs, or rotary member. At the same speed, the power consumption will be more or less proportional to the depth of 80 submergence of the discs, and consequently also to the amount of liquid sprayed. For most purposes good results will be obtained by having a small submergence, or by having the surface of the liquid nearly tangential to the periphery of the discs, or rotary member. Excellent results have been obtained with a submergence of from $\frac{1}{4}$ inch to 1 inch. With discs a foot in diameter and rotating at a speed of 1000 R. P. M., the 85 chamber above the liquid will be filled with a fine mist mixed with a heavier spray, which is thrown from 15 to 20 feet. If this heavier spray is impinged against baffles, or sprayed into a permeable mass such as the 90 scrubbers shown by 21, which act more or less as baffles, the heavier spray is also largely converted into a fine spray or mist. The power consumed when the periphery of the discs has a submergence of about $\frac{1}{4}$ inch below the normal liquid level is very 95 small. Good results in some metallurgical work will be obtained with a depth of liquid of 10 feet, a gaseous atmosphere above the liquid of from 4 to 6 feet, discs having 100 a diameter of one foot, a submergence of from $\frac{1}{4}$ to $\frac{1}{2}$ inch, and a rotary speed of the discs of 1000 R. P. M. These conditions however, may vary greatly, depending on 105 the material being treated and the results 110 desired.

In order to keep the liquid at approximately the same level, irrespective of the volume of flow of liquid, a weir overflow is arranged as shown at 18, Fig. 2, which is 115 arranged so that the liquid may be adjusted to the level desired, and varied as desired, and so that the depth of submergence of the discs will remain constant.

It will usually be desirable to control the 120 temperature of the liquid. For example, in the reduction of ferric salt with sulphur dioxide, the reaction is more efficient at the higher temperatures. At times it may be desirable to cool the liquid, for cooling the gas above the liquid, or possibly to slow down a chemical reaction. If it is desired to cool air, for example, for ventilation purposes, the cooling of the liquid may be desirable. The temperature may be controlled 125 130

by flowing a heating or cooling fluid through the pipes 35 in the bottom of the tank. If the liquid is of a corrosive nature, lead pipes should be used.

- 5 Some chemical reactions may be promoted by the material used in the scrubbers, 21. The reaction, for example, between ferric salts and sulphur dioxide is promoted in the presence of coke or charcoal, as also the 10 action between sulphur dioxide and water in the presence of a material in the towers which may act as a catalytic agent, or as an agent to occlude or concentrate the gas.

There is an advantage in dividing the 15 chamber 1 into sections, as shown in Fig. 2. This arrangement assures the uniform treatment of both the gas and the liquid. All the liquid in one section has got to come to the surface to be sprayed, or come under the influence of the gas, before it can flow into the next section. Similarly, all the gas has got to go through the scrubbers in intimate contact with the liquid, before it can get from one section to the next.

- 25 The quantity of liquid exposed to the action of the gas is very large; in addition to the spray, there will always be a film of liquid at the sides of the tank and on the surface of the material composing the scrubbers. The rapidly rotating discs also expose an enormous surface of constantly changing liquid. If, for example, the discs are a little over a foot in diameter and have a superficial area of two square feet, for 30 both sides, four discs on a shaft, as shown in Fig. 1, and a rotary speed of 1000 R. P. M., there will be exposed a constantly changing surface of liquid of 8,000 sq. feet, per minute.

40 The form of the rotary member may vary considerably. The discs, as shown, are preferred for most purposes. If the discs are made wider, that is to say, more in the form of an ordinary cylinder, the spray will be 45 wider also. The spray will have the same, or nearly the same, width as the width of the disc or cylinder. Other forms of rotary members may be used, but experimentation has shown that a rotary member with a 50 circular periphery will ordinarily give the best results. If rotary sprayers other than discs are used, it will be understood that the circular periphery, or peripheral circle, described by any other form of rotary sprayer, will in effect be the same as the discs.

Under the conditions of operation of this apparatus the liquid below the surface, so far as the discs are concerned, remains practically undisturbed. There is no violent agitation of the mass of the liquid. In this 60 respect the apparatus differs from the ordinary means of treating liquids with gases in which the gas is brought into intimate 65 contact with the liquid by violent agitation

of the entire liquid, or as in the ordinary scrubbing tower in which the liquid is showered through the ascending gas.

There is an advantage in spraying the liquid into the gas as embodied in this invention, in that the effect desired is usually more pronounced than in apparatus ordinarily employed. It is evident that the liquid sprayed at a high speed into the gaseous atmosphere will develop considerable pressure between the gas and the liquid spray, and hence promote the desired chemical reaction between the gas and the liquid, notwithstanding that the gas in the chamber is under a slight suction inwardly.

I claim:

1. In apparatus for treating liquids with gas, a chamber having a liquid inlet and a liquid outlet and a gas inlet and a gas outlet and adapted to contain liquid and to confine gas over the liquid, said chamber being divided into sections in the upper portion with fluid permeable members dividing the sections, partitions in the lower portion of the chamber arranged to give the liquid a sinuous flow through the chamber, means for flowing gas through the chamber and through the permeable members from one section to the next, and means within the sections for spraying liquid into the gas and into the permeable members.

2. In apparatus for treating liquid with gas, a chamber divided into sections each of which is adapted to contain a pool of liquid and to confine gas over the pool, sprayers in the various sections adapted for spraying liquid of the pools into the gas, means for progressively advancing the gas through the liquid sprays over the pools of the various sections, partitions arranged between the pools to give the liquid a sinuous flow from one pool of the series to the next, an overflow liquid outlet from the chamber, said partitions and overflow liquid outlet being arranged to maintain a substantially constant liquid level in all of the pools.

3. In apparatus for treating liquid with gas, a chamber adapted to contain liquid and to confine gas over the liquid, a rotary shaft passing horizontally through the chamber and journaled outside, a spraying member mounted on said shaft and adapted to spray liquid in the lower portion of the chamber into the gas in the upper portion and a projecting member mounted on the shaft between the shaft bearing and the spraying member to protect the exposed shaft and to prevent escaping fluid from the chamber from getting into the shaft bearings.

4. In apparatus for treating liquid with gas, a tank adapted to contain a pool of liquid and to confine gas over the pool, a permeable stationary member within the

tank above the liquid comprising means for occluding gas, a rotary member within the tank contacting with the liquid and with the gas adapted to spray some of the liquid 5 of the pool into the permeable member, and means for supplying gas to the tank.

5. In apparatus for treating liquid with gas, a tank adapted to contain a pool of liquid and to confine gas over the pool, a 10 permeable stationary member within the tank above the liquid adapted to promote chemical reaction between constituents of the gas and constituents of the liquid, spraying means within the chamber for spraying some of the liquid of the pool into the permeable stationary member, and means for supplying gas to the tank.

6. In apparatus for treating liquid with gas, a chamber having a gas inlet and a gas

outlet and a liquid inlet and a liquid outlet and adapted to contain a pool of liquid in its lower portion and to confine gas over the pool, a rotary shaft passing horizontally through the chamber and journaled outside, a spraying member mounted on said shaft 20 adapted to spray liquid from the surface of the pool in the lower portion of the chamber into the gas over the pool, a projecting member mounted on said shaft between the shaft bearing outside of the chamber and the spraying member within the chamber to prevent escaping fluid from the chamber from getting to the exposed shaft or from getting into the shaft bearings, and suction means 25 for flowing gas through the chamber over 30 the pool of liquid.

WILLIAM E. GREENAWALT.
